CONTROLLING SYSTEM.

1,283,826.

Specification of Letters Patent.

Patented Nov. 5, 1913.

Application filed October 11, 1915. Serial No. 55,308.

To all whom it may concern:

Be it known that we, DAVID L. LINDQUIST, a subject of the King of Sweden, and CHARLES B. MANVILLE, a citizen of the 5 United States, residing in Yonkers, in the county of Westchester and State of New York, have invented a new and useful Improvement in Controlling Systems, of which the following is a specification.

10 Our invention relates to an automatic system of electrical control for bell hoisting mechanism for use in connection with blast furnaces.

An object of the invention is the provision 15 of a novel system of electrical control operable automatically to effect the operation of the large and small bells.

Another object of the invention is to provide means by which the sequence of operation 20 between the small and large bell may be changed at will, to suit a number of different charging requirements of the furnace, or in other words these means are for the purpose of selectively predetermining 25 the sequence of operation between the two bells.

A further object is to provide means for effecting an emergency or cleaning operation 30 of the bells, independently of the automatic operation.

Other objects are to provide means for adding an extra skip load to a round, without disrupting the sequence controlling apparatus; and to provide a timing element 35 for automatically controlling the large bell motive means to keep the bell in open position for a pre-determined period of time in order to "breathe" the furnace, and to then automatically complete the cycle of operation 40 by closing the bell.

Other objects will appear hereinafter, the novel combinations of elements being pointed out in the annexed claims.

In charging a blast furnace, the skip is 45 loaded with a predetermined weight of coke, ore, limestone, etc., and discharges its load into a small bell, which is of substantially the same capacity as that of the skip. As soon as the skip load is discharged into the 50 small bell, the latter is raised and delivers its load into a large or mixing bell, which remains closed until it has received a predetermined number of charges of different

materials from the small bell. The large bell is then raised and discharges the mixture 55 into the furnace. This operation requires that the skip and small bell shall perform a predetermined number of cycles of operations before the large bell is operated, and it is one of the objects of our invention 60 to provide automatic means which are selective for controlling the sequence of operation between the large and small bells, and also the sequence of operation between the skips and the said bells.

In the drawings, Figure 1 illustrates a furnace or skip hoist containing an embodiment of our invention; Fig. 2 is a wiring diagram illustrating the electrical controlling system for the small and large bell 70 hoists, together with only such controlling elements for the main skip hoist as are interconnected with the first mentioned electrical controlling system; Fig. 3 illustrates partly in section, a detail view of an electrically operated device for automatically controlling the sequence of operation between the small and large bell hoists, and Figs. 4 and 5 illustrate certain parts of the device as viewed from the front of the 80 Fig. 3.

Referring to Fig. 1, a blast furnace A is charged with ore, limestone, coke, etc., by means of skips L and C, which travel over inclined tracks Q. The skips are connected 85 to opposite ends of a cable E, which is wrapped about a winding drum H, operated by a motor M. The latter is housed in a power house G, which contains the controlling mechanism Z and a master switch 90 Z' for the skip. A floor controller F of a well known type is driven from the main driving shaft J through a sprocket and chain connection K, and the ratio between the sprockets is such that an opening of 95 either of the contacts 46 or 47 is effected when either of the skips approach within a short distance of the lower landing as hereinafter described.

The bells, etc., at the top of the furnace 100 may be of any well known construction, and comprise a receptacle or hopper 1 to receive charges delivered by the skips, said hopper having its lower end closed by a small bell 2. A compartment 3 receives the 105 charge from the hopper 1 when the small

bell is lowered and is closed at the bottom by a large bell 4. The small and large bells are provided with power mechanism X and X' respectively, which are similar in construction, and may be of any well-known construction, and in this instance comprise small electric motors M', M², and electro-mechanical brakes B. The motor M' is provided with a series field winding 19, and 10 a shunt field winding 20, said motor being connected through worm and gearing or other speed reduction mechanism to drive a pinion. An annular gear 7 is in mesh with the pinion, and is connected through a crank 15 shaft connection to a connecting rod 6, connected at one end of a lever 8, to which is connected a walking beam 9. The walking beam associated with the small bell is pivoted at 8' to the overhead framework, one 20 of its ends being connected to a hollow rod or tube 9' which is secured to the small bell. The walking beam 8'' associated with the large bell is pivoted at 10 to an overhead framework, one of its ends being connected 25 to a rod 11, which extends through the tube 9' and is secured to the large bell. A counterweight 12 is guided over a sheave 13, and is connected to the lever 8 associated with the small bell. A counterweight 14 is connected to the lever 8 associated with the 30 large bell.

Cams T and T' on the periphery of the gears 7 and 7', respectively, permit the closing of normally open contacts associated 35 with switches 16 and 17, directly upon the rotation of said gears, and will open said contacts upon a complete revolution of the gears, and thereby effect the stopping of the power mechanism in a manner hereinafter 40 described.

An additional normally closed switch 17' is positioned to be opened by the cam T', when the gear 7' has made approximately one half revolution.

45 Referring now to Fig. 2, in addition to the parts already pointed out, I will now designate the various parts which control the power mechanism X, which actuates the small bell; a direct current source of supply 50 designated + and -; a main line switch P; an accelerating magnet O which controls a starting resistance 18, and series field 19; a shunt field 20; a stopping magnet S which controls the stopping resistance 21; a "making" push button 22; a "breaking" push button 23; a self holding magnet 24; and 55 an auxiliary operating magnet 25; the parts which control the power mechanism X' which actuates the large bell are as follows: 60 a main line switch P'; an accelerating magnet O' which controls a starting resistance 18'; and series field 19'; a shunt field 20', a stopping magnet S' which controls the stopping resistance 21'; a "making" push button 22'; 65 a "breaking" push button 23'; a self holding

magnet 24'; and an auxiliary operating magnet 25'. In addition to these members are contacts 26, adapted to be closed upon the operation of a reversing switch U, and contacts 27, adapted to be closed upon the operation of a reversing switch D. The reversing switches U and D are controlled in a well known manner by the master switch Z', to reverse the current through the skip motor M.

75 Additional parts are a slow closing electro-magnetic switch 104 controlling contacts 105, knife switch 29, and a two blade plug or changeover switch 28 which may be interchanged manually to engage any one set at 80 a time, of the fixed contacts (comprising four to a set), as formed by the squares designated 2, 3, 4 and 6. By means of this knife switch used in conjunction with the electrical distribution device 30, the sequence of operation between the small and large bell hoists, may be changed or predetermined to meet the furnace charging requirements of either 2, 3, 4 or 6 loads, or in other words, the automatic operation of the large bell may be 85 effected after every 2nd, 3rd, 4th or 6th operation of the small bell.

90 The electrical distributor 30, which is illustrated by the Figs. 3, 4 and 5, consists in detail of a casing Y, provided with a removable cover 90 which is secured thereto by the thumb screws 91. A magnet winding 41 is contained in the casing, and its armature 92 is adapted to rotate an electrical conductor ring or distributor 36, through a pawl and 95 ratchet connection. The electrical distributor 36 is rotatable with a shaft 99, but is insulated therefrom by the insulating members 101. The electrical distributor consists substantially of segmental contacts 32, 32', 100 33 and 34, the contacts at their inner ends forming a continuous ring, upon which bears a fixed contact finger 39, which may be termed the supply contact. The segmental contacts 32 and 32' are spaced substantially 105 180° apart, the segmental contacts 33 and 34 being spaced 60° from the contact 32', but on opposite centers relatively with the latter. Additional fixed contact fingers are indicated at 38, 40, 40' and 40''. The segmental contacts 33 and 34 are made shorter 110 in length than the segmental contacts 32 and 32', and are adapted only to engage the fixed contact fingers designated 38 and 40. The segmental contact 32 is of greater length 115 than the contact 33 and 34, and will engage the contact fingers 38, and 40, and also the contact fingers 40' and 40'', the latter two fingers being offset relatively with the fingers 38 and 40, so as not to be engaged by 120 the shorter segmental contacts 33 and 34. The segmental contact 32' is constructed to engage only the contact fingers 40' and 40'', it being split (as indicated in the drawing, Fig. 3), the split portion being in alignment 125 130

with the position of the fixed contact fingers 38 and 40, and thus by this construction the said segmental contact will not engage with the said fingers 38 and 40. The contact fingers 38, 40, 40', etc., are secured to, but insulated from the casing Y. The fingers 38 and 40' are spaced substantially 180° apart, the finger 40 being spaced 60° from the finger 38, and the finger 40' being spaced 30° from the finger 40.

10 The ratchet is fixed on the shaft 99, and the pawl is connected through a vertically guided lever 94 to the magnet armature 92. The ratchet is provided with 12 teeth and 15 the pawl is limited in its upward movement by a stop member 94', so that each operation of the armature 92 effects a 30° rotation of the electrical ring or distributor 30. The lever 94 through its engagement with the 20 bolt heads, seats the armature 92 in its unattracted position. A spring pressed disk 110 bears against the lateral face of the ratchet wheel hub, and serves as a friction brake, to prevent spinning of the ratchet 25 wheel.

30 The segmental contacts coact with the fixed contacts as follows for a given sequence of operation as determined by the position of the knife switch 28, illustrated in Fig. 2 and it will be here noted that the designation of each square designates a corresponding sequence it being necessary to insert the knife switch into the contacts forming the square corresponding to the sequence of operation wanted between the small and large bell hoists.

35 For a frequency of two, the controlling coacting contacts of the electrical distributor are, segmental contacts 32, 33 and 34, and 40 the fixed contacts 38 and 40; for a frequency of three, segmental contacts 32 and 32', and fixed contacts 40' and 40''; for a frequency of four, segmental contacts 32, 33 and 34, and fixed contacts 38; and for a 45 frequency of six, segmental contacts 32 and 32', and fixed contact 40''.

50 In Fig. 2, the electrical distributor just described is illustrated diagrammatically and it will be noted that the fixed contact designated 39 serves as a supply to the segmental contacts 32, 33, etc.

55 The push buttons 22, 23, 22' and 23' are for emergency use only, and are contained in a locked box Z'', which may be placed in a suitable housing located on the upper structure of the furnace, or in the power house G as shown.

60 A brief description of the mode of operation of the floor controller will now be given. The contacts 46 and 47 control a system of circuits arranged to prevent an operation of the small bell other than is intended, as for example, in case the skips are stopped and again started at an intermediate 65 point between the limits of travel. As the

skip L approaches within a short distance of the bottom landing, the contacts 46 are automatically opened, and after said skip has moved a short distance in its ascending direction of travel, the contacts are again 70 closed, as are the contacts 47, which are automatically opened when the skip C approaches within a short distance of the bottom landing, and are again automatically closed after said skip has moved a short distance in its ascending direction of travel. 75

The operation of the various parts shown in Fig. 2 will now be described, and it is to be noted, that when referring to the up and down reversing switches which control the 80 direction of travel of the skips C and L, it will be necessary only to associate said switches with one of the skips. With the parts as shown, the skip C is at its upper limit of travel, said direction of travel being 85 controlled by the up reversing switch U, carrying contacts 26. Assuming now that the skip C has discharged its load into the small bell. Upon the operation of the down reversing switch D, a circuit is established for 90 the winding 48 of the main line switch P, which is as follows: from the + conductor 49, contacts 27, conductor 50, conductor 52, contacts 53, conductors 54 and 56, through the winding 48, conductor 57, back contacts 95 58 on the main line switch P', conductor 59, to the - main line conductor associated with the large bell hoist controller. The main line switch P will now close, thereby establishing circuits for the motor, series 100 field, shunt field and brake magnet winding, the motor circuit being as follows: + conductor, through contacts 60, conductor 61, brush 62, through motor M', brush 63, starting resistance 18, series field 19, conductor 105 64, contacts 65, to - line. The brake circuit branches from conductor 61 at the junction 61', conductor 66, through the winding of the brake mechanism B, conductor 67, contacts 68, conductor 69 to the - line. The 110 shunt field circuit branches from conductor 61 at the junction 61'', conductor 70, through the shunt field winding 20, conductor 71, and is connected at the junction 71' to the conductor 64. The brake mechanism will now 115 release and the motor will operate to effect the opening of the small bell. The accelerating magnet O which is connected across a circuit containing the armature and a portion of the starting resistance, will now operate its contacts successively to short-circuit the starting resistance 18, and series field 19, whereupon the motor will operate as a shunt motor. Directly upon the rotation 120 of the gear 7, the cam T is rotated out of engagement with the roller 82, associated with the switch 16, whereupon the latter will close its double set of contacts 55'' and 55''', the former set establishing a circuit there- 125

130 through which is in parallel with the cir-

- cuit including the contacts 53 heretofore described for the winding of the main line switch P. The contacts 55''' establish a circuit by way of the floor controller contacts 5 for the winding of the magnet 24 as follows: conductor 49', contacts 47, conductor 74, through the contacts 46, the floor controller having operated enough to again close said contacts as heretofore described, conductor 10 75, conductor 52, winding of self holding magnet 24, contact 79, conductor 76, contacts 55''', and conductor 77 to — line. This circuit followed to the conductor 52, it will be noted is in parallel to the circuit controlled by the main line switch contacts 27. The magnet 24 will now operate and open the contacts 53 and close the contacts 79 which establish a self holding circuit for the self holding magnet. It will be seen that 15 20 the contacts 53 which heretofore contained the circuit of the winding of the switch P, are now open, but the circuit for said winding is maintained by the switch 16 as follows: conductor 49, contacts 27, conductor 25 50, conductor 52, contacts 55'', conductor 56, winding of switch P, conductor 57, back contacts 58, conductor 59 to — line.
- One complete revolution of the gear 7 effects the opening and closing of the small bell 2, whereupon the cam will effect the opening of the contacts 55'' and 55''' associated with switch 16, the former contacts opening the circuit of the winding of the switch P. The switch P will now open and 30 35 thereby disconnect the motor from its source of supply, and the brake mechanism, with the assistance of the stopping magnet which controls the resistance 21 to effect a dynamic braking action, will now effect the stopping 40 of the motor.
- It will here be noted that the self holding magnet 24 and floor controller contacts protect against another operation of the hoisting mechanism X, if for any reason the reversing switch D is opened and again closed when the skips are in an intermediate point between the limits of travel. This is so for the reason that the self holding magnet 24 remains energized to keep open the contacts 45 50 55 which are initially included in the circuit of the winding 48, until the floor controller contacts 47 open, which is effected when the skip C approaches within a short distance of the bottom landing, at which time the small bell has been opened and closed and ready for another charge.
- Proceeding now with the operation of the sequence switch and associated parts: With the knife switch 28 inserted in the position 60 indicated in Fig. 2 and with the contacts associated with the controller 30 bearing a relative position as shown, an automatic operation of the large bell hoisting mechanism X' will be effected after every third 65 operation of the small bell; the operation in

detail being as follows: Assuming the switch P in closed position for the operation heretofore described, a circuit is established for the winding 41, as follows: contacts 60, conductor 82', contacts 83, conductor 84, knife switch 29, winding of magnet 41, conductor 64' to — line. The winding 41 now being energized will effect a rotation of the controller 30, thirty degrees, which is effected upon each operation of the switch P, to effect an opening or dumping operation of the small bell. Two more operations of the switch P effects the rotation of the controller sixty degrees, and brings the segmental contact 32' into electrical engagement with the contact 40', and after the switch P is opened (or in order to prevent the simultaneous operation of the power mechanisms X and X') a circuit is established for the winding of the switch P', as follows: + conductor 85, knife switch 29, conductor 86, supply contact 39, segmental contact 32' to contact 40', conductor 90, switch 28 to conductors 87 and 88, back contacts 58, winding of switch P', conductor 89, normally closed switch 17', conductor 89', contacts 53', conductor 90, back contacts 58', conductor 77, to — line. The main line switch P' will now close, thereby establishing circuits for the motor M², brake magnet, etc. The brake mechanism will now release and the motor will now operate, the starting resistance 18' being controlled by the accelerating magnet O'.

It will be pointed out here that in the operation of the large bell, the motor M², operating the same is automatically stopped with the bell in open position, this position of the bell, corresponding to approximately one half revolution of the gear 7'. The bell remains open for a predetermined period of time, which may be varied as desired, and the motor M² is again automatically started to close the said bell.

Continuing now with the operation: directly as the gear 7' is rotated, the cam T' rotatable therewith permits the switch 17 to close its contacts 55, 55', the former contacts controlling a circuit for the potential switch winding, which circuit includes the contacts of the switch 17', and forms a shunt around the contacts 53' of the self holding magnet 24'. The contacts 55' being closed, establish a circuit for the winding 24', which will now operate and open contacts 53' and close its contacts 79', which establish a self holding circuit for the winding 24'. The circuit for the winding 24' branches from the conductor 87 (included in the circuit for the winding of switch P'), at 87', conductor 107, normally closed push button 23', conductor 108, winding 24', conductor 109, contacts 55', and thence by wire 110 to — line. The self holding circuit for the winding 24' is the same as just traced up to 130

and through the winding 24', contacts 79', and thence by way of conductor 110 to the — line. The circuit traced intially for the winding of the switch P' is now open at the contacts 53', but the contacts 55 now maintain a circuit for the said winding, this circuit it being particularly noted, including in series therewith the contacts associated with the switch 17'. Now when the motor 10 M² has rotated the gear 7', approximately one half revolution, corresponding to the open position of the large bell, the cam T' actuates the switch 17', thereby opening the circuit just pointed out for the winding of the switch P'. The latter will now open, causing the motor to be stopped, with the large bell in open position in order to "breathe" the furnace. The timing element for determining the period through which 20 the large bell shall remain open, is effected by means of the slow closing electro-magnetic switch designated 104, this switch having a dash-pot associated therewith which may be adjusted as desired to retard the 25 movement of the magnet armature in its operation to close the contacts 105.

At this point it will be noted that the contacts 58 are included in the circuit for the winding of the switch P', these contacts forming a shunt around a high resistance 30 88'. Now since this resistance is normally short circuited by the said contacts 58, the winding of switch P' will initially receive full current strength, and upon the closing 35 of the said switch, the resistance is inserted, acting then in the capacity of a holding resistance, it allowing sufficient current to pass into the said winding, to keep the said switch closed.

40 The operation of the timing element in conjunction with the associated controlling mechanism will now be described. Assuming the large bell is now in open position, with the switch P' open, a circuit for the 45 winding of the slow closing electromagnet 104 may be traced as follows: This circuit branching from the circuit followed from the winding of switch P', at the junction 104'', thence to the winding of switch 104 by way 50 of conductor 111, conductors 112, and 89' to the contacts 55, and conductor 90 through branch contacts 58' on switch P to the — line. The electro-magnet 104 will now operate slowly to close the contacts 105. The contacts 105 being closed 55 now establish a circuit for the winding of the switch P' which circuit may be traced through the said winding to conductor 89, thence by way of conductor 113 to the contacts 105, conductors 112, 89', contacts 55, conductor 90, through back contacts 58' on switch P to the — line. Now it will be pointed out that the windings of the switches P and 104 are included in the same circuit 60 up to the junction 104'', this circuit includ-

ing the high resistance 88'. When the switch P' is first closed to start the operation of the large bell from its normal or closed position, the resistance 88' is inserted also in the circuit including the winding of 70 the switch 104, and since the electro-magnet switch 104 is slow acting the same has not sufficient time to close its contacts before the resistance 88' is inserted by the opening of the back contacts 58, and thereupon the initial operation of the large bell hoisting mechanism, the switch 104 will remain inoperative.

Continuing now with the operation, the contacts 105, as will be seen, establish a 80 holding circuit for the winding of the switch 104. The switch P' will now close and effect a closing of the large bell, and the gear 7' upon completing one revolution brings the cam T' into engagement with the 85 switch 17, thus opening the contacts 55, 55', and effecting the opening of the switch P' whose winding, together with the self-holding circuit for the winding of switch 104, is contained in the circuit controlled 90 by the contacts 55, which as above stated are now opened. In this manner it will be seen that the motor M² will be automatically stopped with the large bell closed. The self holding circuit for the 95 winding of the self holding magnet 24' is, however, still maintained, this circuit being broken upon the next operation of the switch P, which will effect an operation of the ratchet magnet 41, and thus rotate the 100 segmental contacts 30, disengaging the segmental contact 32' from the contact finger 40', and thereby opening the self-holding circuit for the winding 24' at these points.

Continuing now, and assuming the segmental contact 32' and contact 40' are in 105 electrical engagement. Three more dumping operations of the small bell effects a rotation of the segmental ring, 90 degrees, and brings the segmental contact 32, into 110 electrical engagement with the fixed contact 40''. The circuit for the winding of the switch P' is now closed through these contacts, the latter switch closing, and the remaining elements operating in a manner as 115 heretofore described to effect the automatic operation of the large bell hoisting mechanism.

This sequence of operation between the small and large bell hoisting mechanism continues as long as the knife switch remains inserted in the contacts forming the square designated 3.

Now to change this automatic sequence of operation, say for example from 3 to 6, it is 125 necessary that the segmental contact ring on the electrical distributer be set, to what we will term its starting position, as indicated in the drawing in Fig. 4, this position being readily determined by the arrow indicated, 130

which must be in a vertical position pointing upwardly. The knife switch 28 is now interchanged from the position as now indicated, to the contacts forming the square designated 6. For this sequence of operation the automatic operation of the large bell is controlled (that is in so far as the electrical distributor is concerned), by the segmental contact 32', and the fixed contact 40".

10 From the explanation thus far given it will be seen that any desired frequency of the form herein specified may be obtained simply by inserting the knife switch 28 into the desired set of contacts, and by manually 15 resetting the electrical distributor upon each interchange of the knife switch.

For a frequency of two and four, it is thought not necessary to describe in detail, since the particular contacts on the electrical 20 distributor which coact to effect the automatic operation of the large bell hoisting mechanism for each above-mentioned sequence, are designated herein.

The operation for permitting an extra 25 charge to be dumped into the large bell by the small bell without disrupting the automatic sequence of operation controlled by the controller 30, follows: Assuming now the skip has discharged the sixth load into

30 the small bell, the switch 29 is opened before the reversing switch D is closed to effect the starting of the empty skip downwardly. The opening of the switch 29 prevents the

35 operation of the switch P, which when closed establishes the circuit for the winding 41 as heretofore described. The segmental contact ring up to this time we will assume has now been rotated one hundred and fifty de-

40 grees, and when the empty skip is started, the small bell discharges its load, but the rotation of the segmental contact ring 30 is not effected, the switch 29 being opened. The extra skip load is now dumped into the small

45 bell, and before the empty skip is started down, that is, before the closing of the proper reversing switch is effected by the operator, the small knife switch is closed. The proper reversing switch is now closed,

50 an automatic operation of the small bell effected, and the circuit for the winding 41 now being established, effects the rotation of the controller thirty degrees, which will bring the segmental contacts 32' and 40" into electrical engagement, and upon the

55 opening of the switch P, a circuit is completed for the winding of the magnet P', which will now close, and thereby effect the operation of the large bell as heretofore described.

The mode of operation for permitting an extra load after every third operation of the small bell without destroying the sequence of operation controlled by the electrical dis-

tributer 30 is effected by opening the switch 65 29 after the third skip load has dumped into the small bell and before the circuit is established to start the empty skip in a down direction, and to again close said switch after the extra skip load is dumped into the 70 small bell and before the circuit is established to start the empty skip down.

The buttons 22, 23 and 22', 23', are for emergency use only, the buttons 22, 23, controlling the small bell hoisting mechanism 75 independently of the skip hoist controlling switches U and D. Before operating the small bell hoisting mechanism by means of the buttons 22, 23, the switch 29 is first opened, to protect against an operation of 80 the ratchet magnet 41, which would otherwise operate and disrupt the sequence of operation. A momentary operation of the button 22 closes a circuit for the winding of the switch P, which closes and effects an 85 operation of the small bell hoisting mechanism in the same manner as heretofore described. In this operation the electromagnet switch 25 is self-holding as is the magnet 24, as heretofore described, a momentary operation 90 of the button 23 when the hoisting mechanism stops, restoring these magnets to normal position.

For an emergency operation of the large bell hoisting mechanism, the switch 29 may 95 remain closed. A momentary pressure on the button 22' effects an operation of the large bell hoisting mechanism, in the same manner as effected by means of the electrical distributor, but in this instance independently thereof. The magnet 25' is self holding 100 as is the magnet 24', and after a complete operation of the large bell hoisting mechanism, a momentary pressure on the button 23', restores these magnets to normal 105 positions.

Reviewing briefly the various cycles of operation, it is seen that the operation of the small bell hoisting mechanism is controlled automatically by the skip hoist controlling 110 mechanism; each operation of the small bell effects a rotation of the segmental contact ring, thirty degrees, the segmental ring and its coacting contacts effecting an automatic operation of the large bell hoisting mechanism, after every 2nd, 3rd, 4th or 6th dumping 115 operation of the small bell, as determined by the position of the knife switch 28, it being noted that the large bell is operable automatically only when the switch P is in 120 open position; this feature protecting against a simultaneous opening of the two bells; an extra skip load is permissible, the switch 29 being opened for this operation to prevent disrupting the sequence of operation 125 as controlled by the electrical distributor; in operating the large bell, the hoisting mechanism therefor is stopped for a period of

time (as determined by the setting of the slow closing dash pot switch 104) in order to "breathe" the furnace, the bell being then automatically closed; and finally an emergency operation of either of the two bells 5 may be effected, and without disrupting the said sequency controller.

Having thus described our invention, we claim as new and desire to protect by Letters 10 Patent of the United States:—

1. In means for controlling the operation of blast furnace charging parts, the combination with a large and small bell, separate motors for actuating the bells, a skip, a motor 15 for actuating the skip, electro-magnetic switches controlling the circuits of the skip motor, a source of current supply for the motors, an electromagnetic main line switch dependent on the operation of the first 20 named switches automatically to connect the small bell motor to the source of current supply, an electromagnetic main line switch associated with the large bell motor, a circuit controller controlled automatically by 25 the first named main line switch, said circuit controller arranged automatically to effect the closing of the second main line switch after a certain predetermined number of operations of the small bell, and a manually 30 operative switch operable to change the sequence of operation between the small and large bell.

2. In means for controlling the operation of blast furnace charging parts, the combination with a large and small bell, separate motors for actuating the bells, a skip, a motor for actuating the skip, electro-magnetic switches controlling the circuits of the skip 35 motor, a source of current supply for the motors, an electromagnetic main line switch dependent on the operation of the first named switches, automatically to connect the small bell motor to the source of current supply, an electromagnetic main line switch 40 associated with the large bell motor, a circuit controller controlled automatically by the first named main line switch, said circuit controller arranged automatically to effect the closing of the second main line switch 45 after a certain predetermined number of operations of the small bell, a manually operative switch operable to change the sequence of operation between the small and large bells, and a manually operative switch to 50 permit of one or more extra operations of the small bell motor without disrupting the sequence of operation controlled by the circuit controller.

3. In blast furnace charging parts, a small 60 bell, a motor for actuating the bell, a skip, a motor for actuating the skip, reversing switches associated with the skip motor, a source of current supply, an electromagnetic main line switch operable upon the closing

of either of the first named switches to effect the connection of the small bell motor to its source of current supply, and circuit controlling means associated with the motor operable automatically upon the starting of the motor to maintain the main line 65 switch closed and automatically to effect the opening of the main line switch when the opening and closing of the bell is effected.

4. In blast furnace charging parts, a bell, power mechanism for actuating the same, a skip or hoist circuit controlling mechanism dependent on the operation of the skip, automatically to effect the operation of the bell, and means to prevent a second operation of the bell in case the skip is stopped 70 and again started at any intermediate point in the travel thereof.

5. In blast furnace charging parts, a bell, power mechanism for actuating the same, a skip, or hoist, circuit controlling mechanism dependent on the operation of the skip, automatically to effect the operation of the bell, and means operable automatically to prevent a second operation of the bell in case the skip 80 is stopped and again started at any intermediate point in the travel thereof.

6. In blast furnace charging mechanism, a bell, power mechanism for actuating the bell, a skip, power mechanism therefor, controlling circuits and mechanism dependent on the operation of the skip automatically 95 to effect the operation of the bell, an automatic controller and means controlled thereby operable to prevent another operation of the bell in case the skip is stopped and again started at an intermediate point in its travel.

7. In blast furnace charging parts, a bell, a motor for actuating the same, a skip or hoist, a motor for actuating the same, electro-magnetic switches controlling the circuits of the skip motor, an electro-magnetic main line switch associated with the small bell motor, controlling circuits and mechanism operable upon the closing of any one of the first named switches, automatically 100 to effect the closing of the main line switch, means automatically to effect the opening of the switch after a complete operation of the bell, and means to prevent the closing of the main line switch again, until the skip has 110 discharged its load and is again started.

8. In blast furnace charging parts, a small bell, a motor for actuating the bell, a skip, a motor for actuating the skip, electro-magnetic switches controlling the circuits of the skip motor, a main line switch for controlling the circuits of the bell motor, a winding therefor, a self holding magnet having contacts normally closed and establishing a circuit therethrough for the winding, upon the initial closing of the main line switch, the electromagnet adapted to open circuit the winding through the contacts at 120 125

- a predetermined time after the motor starts, means automatically to maintain a closed circuit for the winding upon the starting of the bell motor, said means being arranged 5 automatically to open the circuit of the winding and thereby effect the stopping of the bell motor after a complete operation of the bell, and means automatically to establish a self holding circuit for the self holding 10 magnet after the skip has traveled a certain predetermined distance, and automatically to open said circuit when the skip approaches within a short distance of its limit of travel.
- 15 9. In means for controlling the operation of blast furnace charging parts, a bell, power mechanism for actuating the bell, controlling mechanism associated with the power mechanism, manually operated means 20 operable to effect the operation of the bell, another manual means, and means controlled thereby operable to prevent a second operation of the large bell, until a manual operation of the second named manually oper- 25 ative means is effected.
10. In means for controlling the operation of blast furnace charging parts, a small and large bell, separate power mechanism for actuating the bells, separate controlling circuits and mechanism associated with the power mechanism, and means automatically 30 to control the sequence of operation between the large and small bells, said means comprising a rotatable electrical conductor ring 35 having a plurality of segmental contacts formed integrally therewith and symmetrically spaced a certain predetermined number of degrees apart, electrically controlled means operable upon each operation of the 40 small bell to effect the rotation of the electrical conductor ring a certain predetermined distance, an electrical conductor adapted to supply an electric current to the conductor ring, and additional electrical conductors positioned to be engaged by the segmental contacts, upon a certain predetermined 45 number of rotations of the electrical conductor ring.
11. In a blast furnace having large and 50 small bells, automatic means for controlling the sequence of operation therebetween, said means comprising a rotatable electrical conductor ring having segmental contacts formed integrally therewith at certain pre- 55 determined distances around the ring, an electromagnet, graduated means controlled thereby operable to effect the rotation of the conductor ring upon each operation of the electromagnet, an electrical supply conductor for the electrical conductor ring, and additional electrical conductors positioned 60 to be engaged by the segmental contacts upon a certain predetermined number of operations of the electromagnets.
12. In means for controlling the operation 65 of blast furnace charging parts, a small and large bell, a motor for actuating the large bell, a source of current supply for the motor, an electro-magnetic main line switch associated with the motor, and a circuit controller for the switch operable automatically to control the sequence of operation between the small bell and the main line switch, said means comprising a plurality 70 of rotatable electrical conductors symmetrically disposed a certain predetermined number of degrees around a central axis, an electrically controlled graduated member operable upon each operation of the small bell to rotate said electrical conductors a certain 75 predetermined number of degrees, an electrical supply conductor common to all of the first named conductors, and additional electrical conductors spaced certain predetermined distances apart, and arranged to 80 be engaged by the rotatable conductors, and thereby automatically effect the closing of the main line switch after a certain predetermined number of operations of the small bell. 90
13. In a blast furnace having a large and small bell, automatic means for controlling the sequence of operation therebetween, said means comprising a casing, a removable cover therefor, an electrical conductor ring 95 inside of the frame, the ring having contact segments formed integrally therewith at predetermined distances around the ring, a shaft carrying the ring, means for insulating the ring from the shaft, bearings formed integrally with the frame to support the shaft, an electromagnet and an armature therefor, a ratchet fixed on the shaft, a pivoted dog co-acting with the ratchet, the dog being operatively connected to the armature through a guiding member which is pivotally connected to said armature, means for 100 adjusting the movements of the armature, an electrical conductor held in fixed position inside of the casing, the conductor 105 adapted permanently to engage the conductor ring, and additional electrical conductors held in fixed position inside of the casing, the conductors being positioned to be engaged by the segmental contacts in a certain predetermined order, and upon a certain predetermined number of operations of the electromagnet. 110
14. In means for controlling the operation 115 of blast furnace charging parts, the combination with a small bell and a large bell, motive means for the bells, and means comprising a change-over switch for selectively determining the sequence of operation between the small and large bells. 120
15. In means for controlling the operation 125 of blast furnace charging parts, the combination with a small and a large bell, motive

- means for the bells, and selective means comprising a change-over switch and an electrical distributor for controlling the sequence of operation between the bells. 5 16. In means for controlling the operation of blast furnace charging parts, the combination with a small and a large bell, independent motive means for the bells, and selective controlling apparatus comprising a change-over switch and an automatically operated electrical distributor for automatically controlling the sequence of operation between the small and large bell motive means. 10 17. In means for controlling the operation of blast furnace charging parts, the combination with a small and a large bell, independent motive means for the bells, controlling apparatus for the motive means, and selective apparatus comprising a change-over switch and an electrical distributor controllable by the small bell controlling apparatus, and interconnected with the large bell controlling apparatus to control the sequence of operation between the said motive devices. 15 18. In means for controlling the operation of blast furnace charging parts, the combination with a small bell and a large bell, motive means for the bells, and selective apparatus comprising a change-over switch and an automatically operated electrical distributor for automatically effecting the operation of the large bell after a number of operations of the small bell as predetermined by the said selective apparatus. 20 19. In means for controlling the operation of blast furnace charging parts, the combination with a small bell and a large bell, motive means for actuating the bells, and selective apparatus for controlling the sequence of operation between the two bells, said apparatus comprising an electrical distributor and a change-over switch. 25 20. In means for controlling the operation of blast furnace charging parts, the combination with a small bell and a large bell motive means for actuating the bells, and selective apparatus controlling the sequence of operation between the two bells, said apparatus comprising an automatically operated circuit controller and a change-over switch. 30 21. In means for controlling the operation of blast furnace charging parts, the combination with a small bell and a large bell, motive means for the bells, and means comprising a change-over switch for determining the sequence of operation between the two bells. 35 22. In means for controlling the operation of blast furnace charging parts, the combination with a small bell and a large bell, motive means for the bells, and selec- 40 45 50 55 60 65 70 75 80 85 90 95 100 105 110 115 120 125
- tive apparatus controlling the sequence of operation between the two bells, said apparatus comprising a change-over switch and a circuit controller controllable by the small bell. 65 23. In means for controlling the operation of blast furnace charging parts, the combination with a small bell and a large bell, motive means for the bells, and a sequence controlling device comprising an electrical distributor, and electrically operated means for actuating the same a predetermined amount. 70 24. In means for controlling the operation of blast furnace charging parts, the combination with a small bell and a large bell, motive means for the bells, and a sequence controlling device comprising an electrical distributor, an electromagnet, and a pawl and ratchet connection between the distributor and the electromagnet. 75 80 85 90 95 100 105 110 115 120 125
25. In means for controlling the operation of blast furnace charging parts, the combination with a small and large bell, motive means for the bells, a sequence controlling means comprising a conductor ring consisting of a number of segmental contacts spaced at a predetermined distance, fixed contacts positioned to coact only with certain predetermined segmental contacts, an electromagnet, and a pawl and ratchet connection between the conductor ring and electromagnet. 90 95
26. In means for controlling the operation of blast furnace charging parts, the combination with a large bell, motive means therefore, an automatic means for stopping the motive means with the bell in open position, and for effecting operation of the motive means. 100
27. In means for controlling the operation of blast furnace charging parts, the combination with a large bell, motive means therefore, and automatic means for stopping the motive means with the bell in open position for a predetermined period of time. 105 110
28. In means for controlling the operation of blast furnace charging parts, the combination with a large bell, motive means for the bell, means for controlling the motive means to open and close the bell, and means for automatically stopping the motive means with the bell in open position for a predetermined period of time. 115
29. In means for controlling the operation of blast furnace charging parts, the combination with a large bell, motive means for the bell, a timing element, and means for automatically stopping the motive means with the bell in open position for a predetermined period of time as determined by the timing element. 120 125
30. In means for controlling the operation of blast furnace charging parts, the combi-

nation with a large bell, a motor operating the bell, apparatus controlling the motor to automatically open and close the bell, a timing element comprising a dashpot elec-
5 tromagnet, and means for automatically stopping the motor with the bell in open position for a period of time as determined by the timing element.

In testimony whereof, we have signed our names to this specification in the presence of two subscribing witnesses.
